Primary Examiner—Nelson C. Holtje*Attorney, Agent, or Firm*—Biebel & French[57]*CLAIM

The ornamental design for a stitched fabric photo album cover kit, as shown and described.

DESCRIPTION

FIG. 1 is an elevational view of the interior of a front cover, backing and rear cover of a stitched fabric photo album cover kit embodying the present invention;

FIG. 2 is an elevational view of the exterior of the front cover, backing and rear cover of the stitched fabric photo album kit embodying the present invention;

FIG. 3 is a top view thereof;

FIG. 4 is a bottom view thereof;

FIG. 5 is a left side view of the front cover, the right side view of the rear cover being a mirror image;

FIG. 6 is a right side view of the front cover, the left side view of the rear cover being a mirror image;

FIG. 7 is a left side edge view of the backing, the right side edge view thereof being a mirror image; and,
